UNITED STATES PATENT OFFICE

2,625,888

RAILWAY TRUCK

Emil H. Blattner and Glenn F. Couch, Rochester,
N. Y., assignors to The Symington-Gould Corporation, Depew, N. Y., a corporation of Maryland

Application September 20, 1945, Serial No. 617,653

30 Claims. (Cl. 105—224)

1

This invention pertains to a railway truck and more particularly to a journal box mounting therefor.

An object of the invention is the provision of an improved journal box mounting whereby a journal box and side frame is arranged for relative transverse and vertical movements with both of these movements controlled or snubbed.

Another object of the invention is the provision of an improved journal box mounting wherein a friction or snubbing means controls definitely and positively relative vertical and transverse movements of a journal box and side frame and the friction means is further arranged to prevent movement of the journal box longitudinally of the side frame.

A feature of the invention resides in a series of resilient means for affording relative vertical and transverse movements of a side frame and journal box with positive acting friction means associated with the resilient means for controlling both of the movements.

A further feature of the invention resides in a nest of friction means expandable in directions at an angle or normal to one another for snubbing both lateral and vertical movements of a journal box and side frame.

The above objects and features as well as numerous others will become apparent from the succeeding description of an illustrative or exemplary form of the invention which is shown in the accompanying drawings wherein:

Figure 1 is a partial front elevational and partial vertical sectional view of a pertinent part of a railway truck embodying the present invention.

Figure 2 is a partial plan and partial horizontal sectional view taken along the lines 2—2 of Figure 1 looking in the direction of the arrows.

Figure 3 is a transverse sectional view taken along the lines 3—3 of Figure 1 looking in the direction of the arrows.

Figure 4 is an exploded perspective view of the friction means which forms a part of the illustrated structure.

Referring now in detail to the drawings, wherein throughout the several views like reference characters indicate like parts, the numeral 1 is employed to designate generally a railway car truck and, as will be observed, only a corner or portion of the entire truck is illustrated in the drawings. The invention relates primarily to an improved support for a side frame 2 and, as is well known by those skilled in the art to which this invention appertains, a railway truck

2

comprises a pair of transversely spaced, longitudinally extending side frames joined intermediate their ends by a bolster (not shown). The side frame intermediate its ends may be of any conventional design in that it contains the usual top or compression member 3 and a lower or tension member 4. The compression and tension members are united adjacent to each extremity of the side frame to present a housing or pocket 5 which is interrupted intermediate its height by a horizontal wall 6 formed by a continuation of a web member 7 of the tension member. The housing is formed in part by two column guides or guideways 8 which open toward one another and also downwardly of the truck. Each guideway comprises an inner or inboard flange 9 and an outer or outboard flange 10 joined adjacent a vertical edge by a web 11 so that each column guide is substantially channel-shaped in horizontal section (see Figure 2) with the pair of substantially counterpart guideways defining a clear or transverse opening 12 therebetween.

Disposed within the transverse opening is a journal box or load carrying member 13 which, as will be recognized by its configuration, is designed for the accommodation of friction bearings but as will be clearly understood may be easily and readily replaced by or exchanged for a journal box suitable for use with roller bearings. The journal box has outstanding therefrom oppositely directed, horizontally disposed shelves, ledges or wings 14 reinforced by suitable underlying, dependent flanges 15 with each wing extending into a related side frame guideway. Because of the desirability of a transverse movement of the journal box relative to the side frame, to be considered more in detail herein-after, each shelf is of a width substantially less than the transverse distance between an adjacent inboard and outboard column flange as clearly shown in Figure 3 of the drawings, with this distance between ledges and flanges being determinative of the permissible lateral journal box movement. At this stage of the description of the illustrated species it is deemed well to point out that a journal box is afforded a transverse movement relative to the side frame to thereby impart a certain degree of flexibility to the truck and therefore the latter is better fitted to lend itself to irregularities in the rails.

The side frame is supported by or connected to the journal box through the medium of mountings characterized by yieldable or resilient means 16 which extend vertically between the side frame 15 and journal box. The greater portion of each

yieldable means is housed within a column guide in vertical alignment with an underlying shelf but, as will be clearly understood, these components need not necessarily be limited to this particular confining relationship. Each specifically illustrated yieldable means comprises a load carrying double coil or helical spring 17 made up of a heavy outer coil spring 18 and a lighter inner coil spring 19 both of which extend through an accommodating aperture 20 in the horizontal wall to have their upper ends bear directly against a downwardly facing spring seat 21 formed on a top web 22 of the compression member. This particular spring disposition affords the use of a spring of relatively long travel and thereby imparts an easy riding or acting quality to the truck structure. However, if for reasons which are quite obvious the use of a shorter travel spring is required, the horizontal wall may be formed devoid of the apertures 20 so that the upper end of each yieldable means may terminate at or bear against the horizontal wall. This modification or alteration is exemplified in the United States Patent 2,180,933 granted November 21, 1939 to D. S. Barrows, and is well within the scope of the present invention.

Acting in series with each double spring is a load carrying, yieldable sandwich 23 comprising upper and lower plates 24 and 25 respectively having bonded thereto pads 26 of resilient or deformable or displaceable material such as rubber, a rubber compound or the like. Interposed between each pair of vertically disposed pads is a spacer or intermediate plate 27 which also has the pads bonded thereto so that the sandwich is formed into a complete or unitary structure or component. While two pads are illustrated in each sandwich, the number of pads which may be employed is of course elective or optional since the characteristics of various compounds are likely to differ widely. Further, while roller means might easily be substituted for the sandwiches to accomplish some of the advantages gained by use of the latter, it is, however, preferred to employ the sandwiches because the rubber or rubberized pads will, when subjected to a superimposed load, readily adjust themselves to thereby compensate for the lack of trueness of related friction surfaces which will hereinafter be considered in detail. Preferably, in this embodiment of the invention, the sandwich at each journal box side is normally subjected to compressive force only, that is to say, when the journal box and side frame are in the particular relationship as shown in the drawings, no horizontal shear forces are acting in the pads and the latter therefore may be considered neutral. Downstanding from each lower plate is a spud 28 extending into an accommodating opening 29 in a related shelf to thus interlock the lower plate and shelf so that they will act in unison. Because, therefore, of the flexible connection between the journal box and side frame, the former is adapted or arranged to be moved in response to external impulses relative to the latter in a direction transversely or laterally of the truck. As will be hereinafter pointed out, the top plate of each sandwich is held stationary when considering horizontal directions so that any transverse movements of the journal box inwardly or outwardly of the truck will result in a gradually increasing development of horizontal shear forces in the pads to build up these internal forces until the journal box shelf comes to rest against either the inboard or out-

board flange. When an external impulse is imparted to the journal box to urge it transversely of the truck it may not be followed immediately by a counterimpulse or an impulse of equal intensity to return the journal box to its normal position. However, in the present invention no counterimpulses are relied upon since the energy built up in the displaced pads tends to return the journal box to its normal position.

10 The pads and coil springs acting in series and considered collectively form relatively live resilient means and it is deemed desirable at the present writing to positively snub or control the action of these resilient elements. Toward the 15 accomplishment of the above there is provided a friction means "A" housed within each guideway and preferably interposed between the coil springs and sandwich at each side of the load carrying member or journal box. Each friction means 20 comprises a shoe 30 having a downwardly facing seat 31 bearing directly upon a top plate of a subjacent sandwich and being provided with downstanding or depending spaced shoulders 32 in abutting or overlapping relationship with the 25 top plate to maintain the latter in a predetermined or fixed position. Each shoe is provided with a vertical inner wall 33 upstanding from a base 34 thereof to be in intimate contact with a replaceable rubbing plate 35 removably secured 30 to the inboard flange of the guideway. Forming a forward continuation of or joined to the inner wall is a vertical side wall 36 which also upstands from the base 34 and is in bearing relation with a wear plate 37 secured to the guideway web by 35 any desired manner or method. During a flexing action of the resilient means which will result in the side frame moving vertically with respect to the journal box, frictional forces will be created on the contiguous surfaces of the shoe 40 walls and described plates of each guideway to assist in snubbing the action of the resilient means.

45 In an elevated position above the base of each shoe is a ring-like or annular spring seat 38 which forms a supporting ledge for the lower extremity of an outer coil of a related double coil spring with the ledge being of substantially the same inner and outer diameter as the outer coil. Spaced posts 39 rise above the base of each shoe beyond the horizontal plane of the annular spring seat to maintain the outer coil spring in a predetermined position. On the outboard side of each shoe there is provided a pocket or recess 40 formed by longitudinally spaced transversely extending vertical walls 41 joined along their inner 50 edges by a canted, inclined or sloping web 42 which reaches up from the base of the shoe. This pocket in each shoe faces outwardly and downwardly of the truck and accommodates a wedge or wedge-shaped member 43 which is confined within the pocket and has an outer, plane, vertical surface 44 bearing directly against a replaceable brushing plate 45 carried by a related outboard flange. Each wedge-shaped member 55 has an inwardly and downwardly directed sloping surface 46 which is correspondingly disposed as or contiguous with a related surface on the sloping web of the shoe. Drillings or cored openings 47 are formed in each wedge and into these openings there extends a pair of light coil springs 48 which act against or are retained within their openings by a subjacent sandwich top plate to urge the wedge upwardly and cause a transverse spreading action of the shoe and wedge. In this manner, therefore, the wedges and shoes are at

all times maintained in intimate contact with the inboard and outboard flange plates to function immediately in the creation of frictional forces upon any vertical flexing action of the resilient means. Because also of this transverse spreading action of the shoes and wedges the top plate of each sandwich is positively retained against the slightest transverse horizontal movement.

Interlaced with or extending into each shoe is an auxiliary or journal box wedge 49 disposed between the shoe web and overlying annular spring seat with each wedge being substantially L-shaped in vertical section to thereby present vertical, transversely spaced legs or barriers 50 arranged to bear against a side wall 51 of the journal box. The barriers are spaced transversely of the truck to accommodate the outer coil spring which extends therebetween. A bed plate 52 of each auxiliary wedge, as previously inferred, extends into a related shoe from the lower extremities of the barriers. Each bed plate has an upwardly facing seat 53 upon which rests a lower extremity of a related inner coil spring 19 the latter of which reaches the auxiliary wedge through the ring-like member of the shoe. On the inner side of each wedge bed plate are a plurality or series of inclined surfaces 54 bearing upon correspondingly formed surfaces 55 on the shoe with both sets of these surfaces sloping downwardly and inwardly toward the journal box so that the superimposed load on the auxiliary wedges acting through the inclined surfaces 54 and 55 will cause a horizontal spreading action of the auxiliary wedge and shoe. This latter spreading action is normal to the spreading action of the shoe and wedge 43 and accordingly the shoe and auxiliary wedge are urged at all times longitudinally of the truck against the related guideway web bearing plate and the journal box. Any vertical flexing action of the resilient means will cause the creation of frictional forces on the contacting surfaces of the shoes and wear plates 37 and journal box to complete the snubbing of the vertical action of the resilient means. The vertical movement between the journal box and auxiliary wedge will of course be slight in the illustrated embodiment of this invention because of the slight vertically flexing action of the pads.

By reason of the particular arrangement of shoe and wedges in each guideway each friction means is maintained substantially horizontally stationary but, as previously pointed out, the journal box is adapted and capable of moving transversely of the truck. This transverse movement is positively snubbed or controlled by the wiping or brushing action of the journal box side walls across the auxiliary wedge barriers.

Also a final observation may be made to the effect that while the journal box is capable of moving transversely of the truck and the side frame is arranged to move vertically relative to the journal box the latter is, however, locked against any movement longitudinally of the side frame and, accordingly, the truck is held against assuming an out-of-square position; that is to say, the side frame of the truck may not be displaced from a true preset, predetermined transverse alignment because of the two sets of friction means acting between the journal box side walls and the side frame at each corner of the truck.

From the above it will be observed that various changes and alterations may be made to the illustrated and described species of the invention.

without departing from within the spirit of the invention and the scope of the appended claims.

We claim:

1. In a railway car truck wherein a side frame and a load carrying member are arranged for relative vertical and transverse movements, the combination of, load carrying spring means disposed between said side frame and load carrying member for permitting said vertical movement, means associated with said load carrying member for allowing said transverse movement, and a nest of friction means between and arranged to frictionally engage said side frame and load carrying means for controlling both of said movements; said nest of friction means being expandable longitudinally and transversely of said truck.
2. In a railway car truck wherein a side frame and a load carrying member are arranged for relative vertical movement, the combination of, double coil load carrying spring means disposed between said side frame and load carrying member for permitting said vertical movement, and multipart friction means between said side frame and load carrying member; said friction means being expendable longitudinally and transversely of said truck and arranged to frictionally engage angularly related surfaces of said side frame for controlling said vertical movement; each coil spring of each spring means acting against a different part of said friction means.
3. In a railway car truck wherein a side frame and a load carrying member are arranged for relative vertical movement, the combination of, multipart load carrying spring means disposed between said side frame and load carrying member for permitting said vertical movement, and multipart friction means between said load carrying spring means and load carrying member, said friction means being expandable horizontally in a direction longitudinally and transversely of said truck and arranged to frictionally engage said side frame for controlling said vertical movement; each part of said spring means acting against a different part of said friction means.
4. In a railway car truck wherein a side frame and a load carrying member are arranged for relative vertical movement, the combination of, load carrying spring means disposed between said side frame and load carrying member for permitting said vertical movement, friction means at each side of said load carrying member engaging said side frame and load carrying member; each of said friction means comprising a shoe having inwardly and outwardly exposed surfaces sloping transversely and longitudinally of said truck, and wedges having sloping surfaces engaging said shoe sloping surfaces, said wedges frictionally engaging said load carrying member and side frame.
5. In a railway car truck wherein a side frame and a load carrying member are arranged for relative vertical movement, the combination of, load carrying spring means disposed between said side frame and load carrying member for permitting said vertical movement, friction means at each side of said load carrying member for snubbing the action of said load carrying spring means, said friction means comprising a shoe engaging angularly disposed surfaces on said side frame and having inclined surfaces sloping longitudinally and transversely of said truck, wedge means engaging angularly disposed surfaces on said side frame and load carrying member and having inclined surfaces engaging said shoe sloping sur-

faces, and auxiliary spring means urging said wedge means against each shoe.

6. In a railway car truck wherein a side frame and a load carrying member are arranged for relative vertical and transverse movements, the combination of, load carrying spring means disposed between said side frame and load carrying member for permitting said vertical movement, means associated with said load carrying member for allowing said transverse movement, and a single unit comprising a nest of friction means between and arranged to frictionally engage said side frame and load carrying means for controlling both of said movements; said means associated with said load carrying member being distorted during a transverse movement of said load carrying member for assisting in returning the latter to neutral position.

7. In a railway car truck wherein a side frame and a load carrying member are arranged for relative vertical movement, the combination of, load carrying spring means disposed between said side frame and load carrying member for permitting said vertical movement, and friction means between said side frame and load carrying member; said friction means comprising a shoe at each side of the load carrying member and engaging a plurality of surfaces of said side frame, a pair of normally acting wedges engaging each shoe, and auxiliary spring means urging each pair of wedges against a related shoe.

8. In a railway car truck wherein a side frame and a load carrying member are arranged for relative vertical movement, the combination of, load carrying spring means disposed between said side frame and load carrying member for permitting said vertical movement, and friction means between said side frame and load carrying member; said friction means comprising a shoe at each side of the load carrying member and engaging a plurality of surfaces of said side frame, a wedge engaging each shoe for urging the latter away from said load carrying member against one of said side frame surfaces, and another wedge engaging each shoe for urging the latter transversely of said truck against another of said side frame surfaces.

9. In a railway car truck wherein a side frame and a load carrying member are arranged for relative vertical movement, the combination of, load carrying spring means disposed between said side frame and load carrying member for permitting said vertical movement, and friction means between said side frame and load carrying member; said friction means comprising a shoe at each side of the load carrying member and engaging a plurality of surfaces of said side frame, a wedge engaging each shoe for urging the latter away from said load carrying member against one of said side frame surfaces, another wedge engaging each shoe for urging the latter transversely of said truck against another of said side frame surfaces, and auxiliary spring means acting against said wedges.

10. In a railway car truck wherein a side frame and a load carrying member are arranged for relative vertical movement, the combination of, load carrying spring means disposed between said side frame and load carrying member for permitting said vertical movement, and friction means between said side frame and load carrying member; said friction means comprising a shoe at each side of the load carrying member and engaging a plurality of surfaces of said side frame, a wedge engaging each shoe for urging

the latter away from said load carrying member against one of said side frame surfaces, another wedge engaging each shoe for urging the latter transversely of said truck against another of said side frame surfaces, and oppositely acting spring means urging said wedges of each friction means toward one another.

11. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for frictionally engaging said side frame and snubbing said vertical movement, wedge means urged by said load carrying spring means against said journal box and shoe means, and auxiliary wedge means interposed between said side frame and shoe means.

12. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for frictionally engaging said side frame and snubbing said vertical movement, wedge means urged by said load carrying spring means against said journal box and shoe means, and auxiliary wedge means interposed between said side frame and shoe means; said first named wedge means frictionally engaging said journal box for snubbing said transverse movement.

13. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for frictionally engaging said side frame and snubbing said vertical movement, and spring-pressed normally acting wedge means disposed between said shoe means, side frame and journal box.

14. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means separating said spring means and displaceable means for frictionally engaging said side frame and snubbing said vertical movement, and a plurality of vertically urged perpendicularly acting wedge means engaging said shoe means, side frame and journal box.

15. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for fric-

tionally engaging said side frame and snubbing said vertical movement, and vertically urged wedge means engaging said shoe means, side frame and journal box.

16. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for frictionally engaging said side frame and snubbing said vertical movement, movable wedge means engaging said shoe means, side frame and journal box, and vertically acting spring means associated with said wedge means.

17. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for frictionally engaging said side frame and snubbing said vertical movement, wedge means interlocked with said shoe means and engaging said journal box, spring means urging said wedge means against said shoe means and journal box, auxiliary wedge means, and auxiliary spring means urging said auxiliary wedge means against said shoe means and side frame.

18. In a railway car truck wherein a side frame and a journal box are arranged for relative vertical and transverse movements, the combination of, load carrying spring means between said side frame and journal box for permitting said vertical movement, displaceable means between said spring means and journal box for allowing said transverse movement, shoe means between said spring means and displaceable means for frictionally engaging said side frame and snubbing said vertical movement, wedge means interlaced with said shoe means and engaging said journal box, spring means urging said wedge means downwardly against said shoe means and journal box, auxiliary wedge means spaced from said first named wedge means, and auxiliary spring means urging said auxiliary wedge means upwardly against said shoe means and side frame.

19. In a railway car truck wherein a side frame and a journal box are arranged for relative vertical and transverse movements, the combination of, load carrying spring means carrying said side frame and comprising an inner coil spring and an outer coil spring, displaceable means carried by said journal box, friction means between said load carrying spring means and displaceable means, said friction means comprising a shoe in engagement with said side frame and carrying said outer coil spring, a wedge in engagement with said journal box and carrying said inner coil spring, and a second wedge in engagement with said shoe and side frame.

20. In a railway car truck wherein a side frame and a journal box are arranged for relative vertical and transverse movements, the combination of, spring means carrying said side frame and comprising an inner coil spring and an outer coil spring, rubber means carried by said journal

box beneath said spring means, friction means between said spring means and rubber means, said friction means comprising a shoe in engagement with said side frame and carrying said outer coil spring, a wedge in engagement with said shoe and journal box and carrying said inner coil spring, and a second wedge in engagement with said shoe and side frame; said shoe and second wedge being arranged to snub said vertical movement, and said first named wedge being arranged to snub said transverse movement.

21. In a railway car truck wherein a side frame and a journal box are arranged for relative vertical and transverse movements, the combination of, coil spring means carrying said side frame, rubber pads interlocked with said journal box and disposed in substantial alignment with said coil spring means, shoe means interlocked with said rubber pads, and spring pressed wedge mean within said shoe means and being urged in a plurality of directions into frictional engagement with said side frame and journal box.

22. In a railway car truck wherein a side frame and a journal box are arranged for relative vertical and transverse movements, the combination of, vertically directed rubbing faces presented by said journal box and side frame; said rubbing faces being disposed at each side of said journal box and spaced apart longitudinally and transversely of said truck, side frame supporting coil springs at each side of said journal box, rubber means carried by said journal box in substantial alignment with said coil springs, and friction means interposed between said coil springs and rubber means; said friction means being moveable in directions transversely and longitudinally of said truck to bear against all of said rubbing faces.

23. In a friction device for use in a railway truck, the combination of, a unitary shoe having angularly arranged outwardly exposed and vertically disposed brushing faces, inclined surfaces within said shoe, and a plurality of wedges engaging said inclined surfaces and having outwardly exposed surfaces arranged to move in directions away from said brushing faces.

24. In a friction device for use in a railway truck, the combination of, a unitary shoe having angularly arranged vertically disposed brushing faces, oppositely exposed inclined surfaces within said shoe, and a plurality of wedges having complementary surfaces engaging said inclined surfaces; said wedges having vertically directed and outwardly exposed faces arranged to move in directions away from said brushing faces.

25. In a friction device for use in a railway truck, the combination of, a unitary shoe having angularly arranged vertically disposed brushing faces, inclined surfaces within said shoe and sloping in directions away from said brushing faces, a plurality of wedges extending within said shoe and having surfaces engaging said inclined surfaces; said wedges having vertical surfaces outwardly of said shoe and arranged to move in directions away from said brushing surfaces.

26. In a friction device for use in a railway truck, the combination of, a shoe having angularly arranged vertically disposed brushing faces, inclined surfaces within said shoe, a plurality of wedges extending into said shoe and bearing against said inclined surfaces for movement of said wedges away from said brushing surfaces, vertically disposed friction surfaces on said wedges outwardly of said shoe, and spring seats on said shoe and wedges.

11

27. In a friction device for use in a railway truck, the combination of, a shoe having angularly arranged vertically disposed brushing faces, inclined surfaces within said shoe and sloping in directions away from one another, wedges extending into said shoe and having surfaces contacting said inclined surfaces, vertically directed faces on said wedges exposed outwardly of said shoe and in directions away from said brushing faces, and spring seats on said shoe and wedges arranged in different planes. 10

28. In a friction device for use in a railway truck, the combination of, a shoe having angularly arranged vertically disposed brushing faces, oppositely exposed inclined surfaces within said shoe, counterurged wedges extending into said shoe and having surfaces engaging said inclined surfaces, and vertical faces on said wedges exposed in directions outwardly of said shoe and away from said brushing faces. 15

29. In a friction device for use in a railway truck, the combination of, a shoe having angularly arranged vertically disposed brushing faces, oppositely exposed inclined surfaces within said shoes and extending in directions away from one another, wedges having inclined surfaces engaging said shoe inclined surfaces, vertical faces on said wedges exposed in a direction outwardly of said shoe and away from said brushing faces, and spring seats on said shoe and wedges, the 25 spring seat on one of said wedges being within the limits of said shoe spring seat. 30

12

30. In a friction device for use in a railway truck, the combination of, a shoe having angularly arranged vertically disposed faces exposed longitudinally and transversely of said truck, 5 inner and outer inclined surfaces carried by said shoe, a wedge engaging said inner inclined surface and having a friction surface exposed outwardly of said shoe and longitudinally of said truck, and a second wedge engaging said outer inclined surface and having a friction surface exposed outwardly of said shoe and transversely of said truck.
